UNITED STATES PATENT OFFICE.

ENGELBERT REUTER, OF NEW YORK, N. Y.

WEAVING-MACHINE.

No. 927,752.

Specification of Letters Patent.

Patented July 13, 1909.

Application filed December 17, 1908. Serial No. 467,932.

To all whom it may concern:

Be it known that I, ENGELBERT REUTER, a subject of the Emperor of Germany, residing at New York city, Manhattan borough, 5 county and State of New York, have invented certain new and useful Improvements in Weaving-Machines, of which the following is a clear, full, and exact description.

This invention relates to a cording device 10 which is adapted to operate in combination with the weaving mechanism of a loom, the function of the said device being not only to produce a cord, but to so manipulate the threads of the braid as to cause the said cord 15 when completed to be firmly interwoven with the threads of the woven material produced by the weaving mechanism of the loom.

As the mode of operation of my improved 20 device will be hereinafter fully described, I will here simply state that the binding element which secures the cord to the woven fabric preferably comprises a central binder, the said binder being a part of the cord, and so manipulated as to cause the shuttle of the 25 loom to pass alternately over and under the said binder as the said shuttle passes between the warp threads of the fabric to be.

I will now proceed to describe my invention, the special features of which will appear 30 in the claims, reference being had to the accompanying drawings forming part hereof, wherein—

Figure 1 is a sectional elevation of one form 35 of loom having my improved device applied thereto, the section being taken on a line *a—a* in Fig. 2; Fig. 2 is a fragmentary sectional top plan view, the section being taken on a line *b—b* in Fig. 1; Fig. 3 is an enlarged detail front view of my improved carrier, 40 upon which the reels of thread for the cord are mounted; Fig. 4 is a rear view thereof showing the pawl which is adapted to partially revolve the carrier at the proper time; Fig. 5 is an enlarged sectional detail view taken on a 45 line *c—c* in Fig. 3; Fig. 6 is an enlarged detail view of the reed of the loom illustrated in Fig. 1; Fig. 7 is a detail diagrammatic sectional view, the section being taken on a line *d—d* in Fig. 1, and shows the course of the 50 operating cables for the carrier-pawl, the reed, and harness of the loom; Fig. 8 is a similar view, the section being taken on a line *e—e* in Fig. 1, and shows the course of the operating cables for the reed and one set

of harness only; Fig. 9 is an enlarged detail 55 perspective view of a common form of shuttle which carries the woof thread; Fig. 10 is an enlarged detail top-plan diagrammatic view showing the manner of locking the cord to the fabric; Fig. 11 is an enlarged sectional 60 view taken on a line *f—f* in Fig. 10; Figs. 12 and 13 are diagrammatic views showing the manner of twisting the cord and locking the binder thereof to the fabric.

Before describing my invention, I will here 65 state that as the weaving mechanism herein illustrated forms no part of my invention, it will be referred to only sufficiently to bring out its coöperation with my improved device; the operation of a loom being well 70 known in the arts.

Referring now to the drawings, 1 indicates a frame, on the rear member 2 of which are supported a plurality of reels 3, 3 and 4, 4 (see Fig. 2). The said reels carry the warp 75 threads 5 and 6, respectively. The threads 5 can be of one color and the threads 6 of another color. The threads 5 and 6 pass under rollers 7 having annular tapered grooves 8 therein to act as guides for the 80 said threads. From the rollers 7 the threads 5 and 6 are passed through the reed 9 pivoted at 10 to the frame 1 of the machine, as shown, the fabric being woven, with the aid of the shuttle 11 (Fig. 9), in the usual manner. 85 The shuttle 11 carries a reel 12 upon which is wound the woof thread 13. Before reaching the reed 9, the threads 5 pass through eyes 14 carried by the set of harness 15, and the threads 6 pass through eyes 16 carried by the 90 set of harness 17. The sets of harness 15 and 17 are carried by bars 18 and 19, respectively, it being understood that each thread 5 and each thread 6 pass through independent eyes.

To raise the threads 5, an operating cable 95 20 in this instance is provided. The said cable passes over an idler 21, under an idler 22, and over idlers 23 and 23^a, and is at its end secured to another cable 24, which at its lower end is secured to a lever 25. The 100 cable 24, above the point of meeting with the cable 20, passes over idlers 26 and 27, and is attached to a lever 28, which is pivotally supported as at 29 to the frame 1. The outer end of the lever 28 operates a depressing rod 30, which at its lower end 31 is adapted to straddle the binder thread 32 of the braid 33 and depress the same. The rod 30

is depressed simultaneously with the raising of the warp threads 5.

To raise the threads 6, a cable 34 is provided which passes over an idler 35 and under an idler 36, and connects with another cable 37, which at its lower end is attached to a lever 38. That part of the cable 37 which is beyond the point of meeting with the cable 34 passes over idlers 39 and 40, and is at its end secured to a pawl 41, which is adapted to intermittently partially rotate the carrier 42, which carries the reels 43 upon which the braid threads 44 are wound. As there are in this instance four reels 43, the carrier 42 will be rotated one quarter of a revolution by the pawl 41 each time that the threads 6 are raised by the harness 17. To prevent the carrier 42 from overreaching, I provide in this instance a spring check 45, which is adapted to lie upon any one of the flat surfaces 46 of a block 47 carried by the carrier 42, when the said carrier is rotated one quarter of a revolution. The carrier 42 is rotatably mounted in a bearing 48, being held in position by a collar 49. The carrier 42 and trunnion carried thereby has a central bore 50, through which the binder thread 32 is adapted to pass, whereby the said thread 32 is located centrally of the cord threads 44. The binder thread 32 is carried by a reel 51 located as shown. Spring retarders 52 (Fig. 1) are in this instance employed to prevent the reels 3, 4 and 51 from paying out too rapidly when the threads 5, 6 and 32, respectively, are raised or lowered.

To enable the carrier 42 to be rotated, I have provided the same with pins 53 (Figs. 1 and 4) with which the pawl 41 can engage. The pawl 41 is returned after each operation thereof by a spring 54. The sets of harness 15 and 17 are returned after each operation thereof by springs 55 and 56, respectively, and the reed 9 by a spring 57. To raise the levers 25 and 38 after each operation thereof, I provide springs 58 and 59, respectively.

As is well known in this art, the sets of harness 15 and 17 are caused to alternately raise the warp threads 5 and 6, respectively, in order that the shuttle 11 can alternately carry the woof thread 13 over and under the said warp threads. As the operations of the sets of harness 15 and 17 are controlled by the levers 25 and 38, respectively, I, for the sake of illustration, have herein employed cams 60, 61, which are adapted to depress the levers 25 and 38, respectively, as the shaft 62 is by any means, in this instance a belt driven pulley 63, rotated. To collect the material as woven, I provide a rotatable drum 64. The complete article comprising the fabric and interwoven cord is indicated by 65.

Referring now to my improved cording attachment, it will be seen by referring to Figs. 3, 4 and 5 that the reels 43 are pivotally mounted in brackets 66 carried by the car-

rier 42. To prevent the reels 43 from paying out too fast, I provide retarders 67, which are kept in firm contact with the threads on the reels 43 by a spring 68, the retarders being pivotally mounted in brackets 69. To still further put a tension on the threads 44, I pass the threads through an eye 70 of a resilient tension member 71. The thread 32, which comprises the binder for the cord, passes directly under the depressing rod 30, 75 as can be seen in Fig. 2. As the reed 9 must be swung rearwardly at each operation of the sets of harness 15 and 17, I connect the frame 72 of the said reed to the cables 20 and 34 by means of the cables 72^a (Fig. 1). It may here be stated that I can place as many reels 43 upon the carrier 42 as I desire, the extent of the partial rotation of the carrier being determined by the number of reels. For instance, if I use six reels, the carrier 42 will be moved one-sixth of a revolution every time the warp threads 6 are raised. For the sake of simplicity, I have omitted automatic means for passing the shuttle through the warp threads 5 and 6, it being understood that the said shuttle will be operated manually.

I will now proceed to describe the operation of interweaving the binder of the cord with the threads of the fabric, reference being had to Figs. 11 to 13 inclusive. When the lever 25 is depressed to raise the warp threads 5, the depressing rod 30 will be forced downwardly and depress the binder 32, and the reed 9 will be drawn backwardly (see Fig. 12). This action will separate the warp threads 5 and 6 sufficiently to permit the shuttle 11 to be passed through the gap and over the binder 32. After the shuttle has been passed through, the lever 25 will rise, the depressing rod 30 will rise, the spring take-up 73 will pull the binder 32 taut, and the reed 9 will go forward and push the woof thread 13, just woven, up against the threads of the previously woven fabric 74. When this action has taken place, the lever 38 will be depressed and raise the thread 6 to the position previously occupied by the thread 5 (see Fig. 13). As the thread 6 is raised the pawl 41 will rotate the carrier one quarter of a revolution and the threads 43 will be given a partial turn around the binder thread 32; the woof thread 13 will then be positioned between the threads 43 and binder 32, but above the warp thread 6. As the thread 5 is now the under thread, the shuttle will be passed through the gap again over the thread 5, but under the binder 32. The next operation will bring the mechanism and threads to the position shown in Fig. 12, and the operation of passing the woof thread over the binder will repeat. Briefly, my improved operation of weaving a cord integral with the threads of a woven fabric consists in causing the shuttle to alternately pass over and under the threads 43 and 32, and the carrier 42 will be rotated one quarter of a revolution each time the shuttle passes over the binder 32. The operation of the carrier 42 will be controlled by the pawl 41, which will be rotated by the lever 25, and the lever 25 will be controlled by the cams 60, 61, which will be rotated by the shaft 62. The cams 60, 61 will be controlled by the levers 25 and 38, which will be controlled by the sets of harness 15 and 17. The sets of harness 15 and 17 will be controlled by the levers 25 and 38, which will be controlled by the cams 60, 61, which will be rotated by the shaft 62. The shaft 62 will be rotated by the pulley 63, which will be rotated by the belt 64. The belt 64 will be rotated by the motor 65. The motor 65 will be controlled by the switch 66. The switch 66 will be controlled by the button 67. The button 67 will be controlled by the hand 68. The hand 68 will be controlled by the eye 69. The eye 69 will be controlled by the head 70. The head 70 will be controlled by the brain 71. The brain 71 will be controlled by the nerves 72. The nerves 72 will be controlled by the muscles 73. The muscles 73 will be controlled by the tendons 74. The tendons 74 will be controlled by the bones 75. The bones 75 will be controlled by the skin 76. The skin 76 will be controlled by the hair 77. The hair 77 will be controlled by the scalp 78. The scalp 78 will be controlled by the brain 79. The brain 79 will be controlled by the nerves 80. The nerves 80 will be controlled by the muscles 81. The muscles 81 will be controlled by the tendons 82. The tendons 82 will be controlled by the bones 83. The bones 83 will be controlled by the skin 84. The skin 84 will be controlled by the hair 85. The hair 85 will be controlled by the scalp 86. The scalp 86 will be controlled by the brain 87. The brain 87 will be controlled by the nerves 88. The nerves 88 will be controlled by the muscles 89. The muscles 89 will be controlled by the tendons 90. The tendons 90 will be controlled by the bones 91. The bones 91 will be controlled by the skin 92. The skin 92 will be controlled by the hair 93. The hair 93 will be controlled by the scalp 94. The scalp 94 will be controlled by the brain 95. The brain 95 will be controlled by the nerves 96. The nerves 96 will be controlled by the muscles 97. The muscles 97 will be controlled by the tendons 98. The tendons 98 will be controlled by the bones 99. The bones 99 will be controlled by the skin 100. The skin 100 will be controlled by the hair 101. The hair 101 will be controlled by the scalp 102. The scalp 102 will be controlled by the brain 103. The brain 103 will be controlled by the nerves 104. The nerves 104 will be controlled by the muscles 105. The muscles 105 will be controlled by the tendons 106. The tendons 106 will be controlled by the bones 107. The bones 107 will be controlled by the skin 108. The skin 108 will be controlled by the hair 109. The hair 109 will be controlled by the scalp 110. The scalp 110 will be controlled by the brain 111. The brain 111 will be controlled by the nerves 112. The nerves 112 will be controlled by the muscles 113. The muscles 113 will be controlled by the tendons 114. The tendons 114 will be controlled by the bones 115. The bones 115 will be controlled by the skin 116. The skin 116 will be controlled by the hair 117. The hair 117 will be controlled by the scalp 118. The scalp 118 will be controlled by the brain 119. The hair 173 will be controlled by the scalp 174. The scalp 174 will be controlled by the brain 175. The brain 175 will be controlled by the nerves 176. The nerves 176 will be controlled by the muscles 177. The muscles 177 will be controlled by the tendons 178. The tendons 178 will be controlled by the bones 179. The bones 179 will be controlled by the skin 180. The skin 180 will be controlled by the hair 181. The hair 181 will be controlled by the scalp 182. The scalp 182 will be controlled by the brain 183. The brain 183 will be controlled by the nerves 184. The nerves 184 will be controlled by the muscles 185. The muscles 185 will be controlled by the tendons 186. The tendons 186 will be controlled by the bones 187. The bones 187 will be controlled by the skin 188. The skin 188 will be controlled by the hair 189. The hair 189 will be controlled by the scalp 190. The scalp 190 will be controlled by the brain 191. The brain 191 will be controlled by the nerves 192. The nerves 192 will be controlled by the muscles 193. The muscles 193 will be controlled by the tendons 194. The tendons 194 will be controlled by the bones 195. The bones 195 will be controlled by the skin 196. The skin 196 will be controlled by the hair 197. The hair 197 will be controlled by the scalp 198. The scalp 198 will be controlled by the brain 199. The brain 199 will be controlled by the nerves 200. The nerves 200 will be controlled by the muscles 201. The muscles 201 will be controlled by the tendons 202. The tendons 202 will be controlled by the bones 203. The bones 203 will be controlled by the skin 204. The skin 204 will be controlled by the hair 205. The hair 205 will be controlled by the scalp 206. The scalp 206 will be controlled by the brain 207. The brain 207 will be controlled by the nerves 208. The nerves 208 will be controlled by the muscles 209. The muscles 209 will be controlled by the tendons 210. The tendons 210 will be controlled by the bones 211. The bones 211 will be controlled by the skin 212. The skin 212 will be controlled by the hair 213. The hair 213 will be controlled by the scalp 214. The scalp 214 will be controlled by the brain 215. The brain 215 will be controlled by the nerves 216. The nerves 216 will be controlled by the muscles 217. The muscles 217 will be controlled by the tendons 218. The tendons 218 will be controlled by the bones 219. The bones 219 will be controlled by the skin 220. The skin 220 will be controlled by the hair 221. The hair 221 will be controlled by the scalp 222. The scalp 222 will be controlled by the brain 223. The brain 223 will be controlled by the nerves 224. The nerves 224 will be controlled by the muscles 225. The muscles 225 will be controlled by the tendons 226. The tendons 226 will be controlled by the bones 227. The bones 227 will be controlled by the skin 228. The skin 228 will be controlled by the hair 229. The hair 229 will be controlled by the scalp 230. The scalp 230 will be controlled by the brain 231. The brain 231 will be controlled by the nerves 232. The nerves 232 will be controlled by the muscles 233. The muscles 233 will be controlled by the tendons 234. The tendons 234 will be controlled by the bones 235. The bones 235 will be controlled by the skin 236. The skin 236 will be controlled by the hair 237. The hair 237 will be controlled by the scalp 238. The scalp 238 will be controlled by the brain 239. The brain 239 will be controlled by the nerves 240. The nerves 240 will be controlled by the muscles 241. The muscles 241 will be controlled by the tendons 242. The tendons 242 will be controlled by the bones 243. The bones 243 will be controlled by the skin 244. The skin 244 will be controlled by the hair 245. The hair 245 will be controlled by the scalp 246. The scalp 246 will be controlled by the brain 247. The brain 247 will be controlled by the nerves 248. The nerves 248 will be controlled by the muscles 249. The muscles 249 will be controlled by the tendons 250. The tendons 250 will be controlled by the bones 251. The bones 251 will be controlled by the skin 252. The skin 252 will be controlled by the hair 253. The hair 253 will be controlled by the scalp 254. The scalp 254 will be controlled by the brain 255. The brain 255 will be controlled by the nerves 256. The nerves 256 will be controlled by the muscles 257. The muscles 257 will be controlled by the tendons 258. The tendons 258 will be controlled by the bones 259. The bones 259 will be controlled by the skin 260. The skin 260 will be controlled by the hair 261. The hair 261 will be controlled by the scalp 262. The scalp 262 will be controlled by the brain 263. The brain 263 will be controlled by the nerves 264. The nerves 264 will be controlled by the muscles 265. The muscles 265 will be controlled by the tendons 266. The tendons 266 will be controlled by the bones 267. The bones 267 will be controlled by the skin 268. The skin 268 will be controlled by the hair 269. The hair 269 will be controlled by the scalp 270. The scalp 270 will be controlled by the brain 271. The brain 271 will be controlled by the nerves 272. The nerves 272 will be controlled by the muscles 273. The muscles 273 will be controlled by the tendons 274. The tendons 274 will be controlled by the bones 275. The bones 275 will be controlled by the skin 276. The skin 276 will be controlled by the hair 277. The hair 277 will be controlled by the scalp 278. The scalp 278 will be controlled by the brain 279. The brain 279 will be controlled by the nerves 280. The nerves 280 will be controlled by the muscles 281. The muscles 281 will be controlled by the tendons 282. The tendons 282 will be controlled by the bones 283. The bones 283 will be controlled by the skin 284. The skin 284 will be controlled by the hair 285. The hair 285 will be controlled by the scalp 286. The scalp 286 will be controlled by the brain 287. The brain 287 will be controlled by the nerves 288. The nerves 288 will be controlled by the muscles 289. The muscles 289 will be controlled by the tendons 290. The tendons 290 will be controlled by the bones 291. The bones 291 will be controlled by the skin 292. The skin 292 will be controlled by the hair 293. The hair 293 will be controlled by the scalp 294. The scalp 294 will be controlled by the brain 295. The brain 295 will be controlled by the nerves 296. The nerves 296 will be controlled by the muscles 297. The muscles 297 will be controlled by the tendons 298. The tendons 298 will be controlled by the bones 299. The bones 299 will be controlled by the skin 300. The skin 300 will be controlled by the hair 301. The hair 301 will be controlled by the scalp 302. The scalp 302 will be controlled by the brain 303. The brain 303 will be controlled by the nerves 304. The nerves 304 will be controlled by the muscles 305. The muscles 305 will be controlled by the tendons 306. The tendons 306 will be controlled by the bones 307. The bones 307 will be controlled by the skin 308. The skin 308 will be controlled by the hair 309. The hair 309 will be controlled by the scalp 310. The scalp 310 will be controlled by the brain 311. The brain 311 will be controlled by the nerves 312. The nerves 312 will be controlled by the muscles 313. The muscles 313 will be controlled by the tendons 314. The tendons 314 will be controlled by the bones 315. The bones 315 will be controlled by the skin 316. The skin 316 will be controlled by the hair 317. The hair 317 will be controlled by the scalp 318. The scalp 318 will be controlled by the brain 319. The brain 319 will be controlled by the nerves 320. The nerves 320 will be controlled by the muscles 321. The muscles 321 will be controlled by the tendons 322. The tendons 322 will be controlled by the bones 323. The bones 323 will be controlled by the skin 324. The skin 324 will be controlled by the hair 325. The hair 325 will be controlled by the scalp 326. The scalp 326 will be controlled by the brain 327. The brain 327 will be controlled by the nerves 328. The nerves 328 will be controlled by the muscles 329. The muscles 329 will be controlled by the tendons 330. The tendons 330 will be controlled by the bones 331. The bones 331 will be controlled by the skin 332. The skin 332 will be controlled by the hair 333. The tendons 490 will be controlled by the bones 491. The bones 491 will be controlled by the skin 492. The skin 492 will be controlled by the hair 493. The hair 493 will be controlled by the scalp 494. The scalp 494 will be controlled by the brain 495. The brain 495 will be controlled by the nerves 496. The nerves 496 will be controlled by the muscles 497. The muscles 497 will be controlled by the tendons 498. The tendons 498 will be controlled by the bones 499. The bones 499 will be controlled by the skin 500. The skin 500 will be controlled by the hair 501. The hair 501 will be controlled by the scalp 502. The scalp 502 will be controlled by the brain 503. The brain 503 will be controlled by the nerves 504. The nerves 504 will be controlled by the muscles 505. The muscles 505 will be controlled by the tendons 506. The tendons 506 will be controlled by the bones 507. The bones 507 will be controlled by the skin 508. The skin 508 will be controlled by the hair 509. The hair 509 will be controlled by the scalp 510. The scalp 510 will be controlled by the brain 511. The brain 511 will be controlled by the nerves 512. The nerves 512 will be controlled by the muscles 513. The muscles 513 will be controlled by the tendons 514. The tendons 514 will be controlled by the bones 515. The bones 515 will be controlled by the skin 516. The skin 516 will be controlled by the hair 517. The hair 517 will be controlled by the scalp 518. The scalp 518 will be controlled by the brain 519. The brain 519 will be controlled by the nerves 520. The nerves 520 will be controlled by the muscles 521. The muscles 521 will be controlled by the tendons 522. The tendons 522 will be controlled by the bones 523. The bones 523 will be controlled by the skin 524. The skin 524 will be controlled by the hair 525. The hair 525 will be controlled by the scalp 526. The scalp 526 will be controlled by the brain 527. The brain 527 will be controlled by the nerves 528. The nerves 528 will be controlled by the muscles 529. The muscles 529 will be controlled by the tendons 530. The tendons 530 will be controlled by the bones 531. The bones 531 will be controlled by the skin 532. The skin 532 will be controlled by the hair 533. The hair 533 will be controlled by the scalp 534. The scalp 534 will be controlled by the brain 535. The brain 535 will be controlled by the nerves 536. The nerves 536 will be controlled by the muscles 537. The muscles 537 will be controlled by the tendons 538. The tendons 538 will be controlled by the bones 539. The bones 539 will be controlled by the skin 540. The skin 540 will be controlled by the hair 541. The hair 541 will be controlled by the scalp 542. The scalp 542 will be controlled by the brain 543. The brain 543 will be controlled by the nerves 544. The nerves 544 will be controlled by the muscles 545. The muscles 545 will be controlled by the tendons 546. The tendons 546 will be controlled by the bones 547. The bones 547 will be controlled by the skin 548. The skin 548 will be controlled by the hair 549. The hair 549 will be controlled by the scalp 550. The scalp 550 will be controlled by the brain 551. The brain 551 will be controlled by the nerves 552. The nerves 552 will be controlled by the muscles 553. The muscles 553 will be controlled by the tendons 554. The tendons 554 will be controlled by the bones 555. The bones 555 will be controlled by the skin 556. The skin 556 will be controlled by the hair 557. The hair 557 will be controlled by the scalp 558. The scalp 558 will be controlled by the brain 559. The brain 559 will be controlled by the nerves 560. The nerves 560 will be controlled by the muscles 561. The muscles 561 will be controlled by the tendons 562. The tendons 562 will be controlled by the bones 563. The bones 563 will be controlled by the skin 564. The skin 564 will be controlled by the hair 565. The hair 565 will be controlled by the scalp 566. The scalp 566 will be controlled by the brain 567. The brain 567 will be controlled by the nerves 568. The nerves 568 will be controlled by the muscles 569. The muscles 569 will be controlled by the tendons 570. The tendons 570 will be controlled by the bones 571. The bones 571 will be controlled by the skin 572. The skin 572 will be controlled by the hair 573. The hair 573 will be controlled by the scalp 574. The scalp 574 will be controlled by the brain 575. The brain 575 will be controlled by the nerves 576. The nerves 576 will be controlled by the muscles 577. The muscles 577 will be controlled by the tendons 578. The tendons 578 will be controlled by the bones 579. The bones 579 will be controlled by the skin 580. The skin 580 will be controlled by the hair 581. The hair 581 will be controlled by the scalp 582. The scalp 582 will be controlled by the brain 583. The brain 583 will be controlled by the nerves 584. The nerves 584 will be controlled by the muscles 585. The muscles 585 will be controlled by the tendons 586. The tendons 586 will be controlled by the bones 587. The bones 587 will be controlled by the skin 588. The skin 588 will be controlled by the hair 589. The hair 589 will be controlled by the scalp 590. The scalp 590 will be controlled by the brain 591. The brain 591 will be controlled by the nerves 592. The nerves 592 will be controlled by the muscles 593. The muscles 593 will be controlled by the tendons 594. The tendons 594 will be controlled by the bones 595. The bones 595 will be controlled by the skin 596. The skin 596 will be controlled by the hair 597. The hair 597 will be controlled by the scalp 598. The scalp 598 will be controlled by the brain 599. The brain 599 will be controlled by the nerves 600. The nerves 600 will be controlled by the muscles 601. The muscles 601 will be controlled by the tendons 602. The tendons 602 will be controlled by the bones 603. The bones 603 will be controlled by the skin 604. The skin 604 will be controlled by the hair 605. The hair 605 will be controlled by the scalp 606. The scalp 606 will be controlled by the brain 607. The brain 607 will be controlled by the nerves 608. The nerves 608 will be controlled by the muscles 609. The muscles 609 will be controlled by the tendons 610. The tendons 610 will be controlled by the bones 611. The bones 61

der a central binder in the cord simultaneously with the operation of weaving the fabric and between said operations of twisting the cord.

5 Having now described my invention, what I claim and desire to secure by Letters Patent is:

1. In combination with the weaving mechanism of a loom, a cording device comprising 10 a carrier, a plurality of reels of cord threads carried by said carrier, means adapted to guide a binding thread centrally of said cord threads, means adapted to depress said binding thread below the line of movement of the 15 shuttle of said loom, whereby the woof thread carried by said shuttle can pass over said binder, and means adapted to twist said cord threads partially around said binding thread after said shuttle has passed there- 20 over.

2. In a fabric weaving device, means adapted to part a plurality of groups of warp threads at intervals, a shuttle adapted to pass between said groups when parted, means 25 adapted to form a cord simultaneously with the weaving of the fabric, said means comprising a rotary carrier, a plurality of reels of cord thread carried thereby, means adapted to partially rotate said carrier at intervals, means adapted to guide a binding thread centrally of said cord threads, and a 30 depressing device adapted to depress said binding thread below the line of movement of said shuttle at every other operation of said shuttle, whereby said shuttle will pass over said binding thread as it passes between said warp threads.

3. In a fabric weaving device, means adapted to part a plurality of groups of warp 40 threads at intervals, a shuttle adapted to pass between said groups when parted, means adapted to form a cord simultaneously with the weaving of the fabric, said means comprising a rotary carrier, a plurality of reels of 45 cord thread carried thereby, means adapted to partially rotate said carrier at intervals, means adapted to guide a binding thread centrally of said cord threads and a depressing device adapted to depress said binding 50 thread below the line of movement of said shuttle at every other operation of said shuttle, whereby said shuttle will pass over said binding thread as it passes between said warp threads, said binding thread being de- 55 pressed simultaneously with the parting of the groups of warp threads.

4. In a fabric weaving device, means adapted to part a plurality of groups of warp threads at intervals, a shuttle adapted to 60 pass between said groups when parted, means adapted to form a cord simultaneously with the weaving of the fabric, said means comprising a rotary carrier, a plurality of reels of 65 cord thread carried thereby, means adapted to partially rotate said carrier at intervals,

means adapted to guide a binding thread centrally of said cord threads, and means adapted to cause said shuttle to pass over said binding thread at every other passage of said shuttle between said warp threads, said 70 carrier being partially rotated at intervals simultaneously with the parting of said groups of warp threads.

5. In a fabric weaving device, means adapted to part a plurality of groups of warp 75 threads at intervals, a shuttle adapted to pass between said groups when parted, means adapted to form a cord simultaneously with the weaving of the fabric, said means comprising a rotary carrier, a plurality of reels of 80 cord thread carried by said carrier, a plurality of pins carried by said carrier, there being one pin for each one of said reels, a pawl adapted to engage said pins independently and at intervals, means adapted to 85 guide a binding thread centrally of said cord threads, a depressing device adapted to depress said binding thread below the line of movement of said shuttle and every other operation of said shuttle, whereby said shuttle will pass over said binding thread as it 90 passes between said warp thread, means adapted to rotate said rotary carrier and means adapted to actuate said binding thread depressing device between the intervals of 95 actuation of said rotary carrier.

6. In a fabric weaving device, means adapted to part a plurality of groups of warp threads at intervals, said group parting means being adapted to part said groups of warp 100 threads alternately, a shuttle adapted to pass between said groups when parted, means adapted to form a cord simultaneously with the weaving of the fabric, said means comprising a rotary carrier, a plurality of reels of 105 cord thread carried thereby, means adapted to rotate said carrier at intervals, said carrier being rotated simultaneously with the parting of the warp threads for the passage there- through of the shuttle, means adapted to 110 guide a binding thread centrally of said cord threads, a depressing device adapted to depress said binding thread below the line of movement of said shuttle, and means adapted to actuate said depressing device, when said 115 warp threads are parted for the return of said shuttle, whereby said shuttle is caused to pass over said binding thread.

7. In a fabric weaving device, means adapted to part a plurality of groups of warp 120 threads at intervals, a shuttle adapted to pass through said groups when parted, means adapted to form a cord, simultaneously with the weaving of the fabric, said means comprising a rotary carrier, said carrier being 125 disposed centrally of said groups of warp threads, a plurality of reels of cord thread carried by said carrier, a reed adapted for the passage through of said warp threads and said cord threads, said cord threads passing 130

through said reed in line with the said rotary carrier whereby said cord threads are disposed centrally of said warp threads, means adapted to guide a binder centrally of said cord threads and adapted to also pass through said reed, and a depressing device adapted to depress said binder below the line of movement of said shuttle at every other

shot thereof, whereby said binder is interwoven with the threads of said fabric. 10

Signed at New York city, N. Y., this 15th day of December, 1908.

ENGELBERT REUTER.
